UNITED STATES PATENT OFFICE.

GEORGE I. CHITTENDEN, OF CLEVELAND, OHIO.

HANGER FOR WALL-RADIATORS.

1,172,582.

Specification of Letters Patent. Patented Feb. 22, 1916.

Application filed March 19, 1914. Serial No. 825,733.

To all whom it may concern:

Be it known that I, GEORGE I. CHITTENDEN, a citizen of the United States, residing at Cleveland, in the county of Cuyahoga and

5 State of Ohio, have invented a certain new and useful Improvement in Hangers for Wall-Radiators, of which the following is a full, clear, and exact description.

This invention relates to hangers for wall 10 radiators and has for its chief object to provide a hanger which is more efficient and satisfactory than the hangers which have been used heretofore.

More specifically considered, the invention 15 aims to provide a hanger which is less susceptible to breakage either before or after the hanger is put into use, and which admits of closer or more accurate adjustment of the radiator engaging parts than is possible with 20 prior hangers which have been put into practical use.

Still further, the invention aims to provide a construction wherein a radiator supporting rod which is normally supported by 25 a bracket which in turn is secured to the wall may be assembled or removed without the necessity of securing the bracket to the wall at a distance from the floor equal to the full length of the rod.

30 The above and other objects are accomplished by my invention, which may be briefly summarized as consisting in certain novel combinations and arrangements of parts and details of construction which will 35 be described in the specification and set forth in the appended claims.

In the accompanying sheet of drawings, 40 wherein I have shown the preferred embodiment of my invention, Figure 1 is a perspective view of the hanger as a whole, with the parts in assembled relationship; Fig. 2 is a side view of the hanger showing the manner in which it is supported from the wall and showing the way it supports the 45 radiator, the latter being shown by dotted lines; Fig. 3 is a sectional view through the hanger substantially along the line 3—3 of Fig. 2, the parts being shown on an enlarged scale.

50 The hanger constructed in accordance with my invention, includes supporting means adapted to be attached to the wall, this supporting means being preferably formed from one piece, and being here shown in the 55 form of a bracket 10, which is adapted to be attached to the wall by bolts 11 or equivalent

means, said bracket including a straight back portion which engages the wall and outstanding ears 12, which are bent at right angles to the body portion. The bracket 10 60 is preferably formed from a strip or bar of wrought iron which can be readily bent to shape, and is not easily broken.

The hanger includes also a rod 13, the upper part of which is round, and is threaded 65 to receive nuts to be referred to presently, and the lower part of which is flattened or of rectangular shape in cross section, as shown at 14. At its extreme lower end, the rod is bent laterally, forming a lower seat 15 for 70 the radiator, which is shown by dotted lines at 16. The seat 15 may be provided with rollers 17 upon which the radiator may rest in the manner shown so as to permit slight movement endwise of the radiator, due to expansion or contraction. I do not regard the rollers, however, as essential in the construction. 75

The rod 13 passes through both the upper and lower ears 12 of the bracket 10, the upper ear having a round opening through which the rod passes, and the lower ear having a rectangular shaped opening to accommodate the rectangular lower part of the rod, this being shown particularly in Figs. 80 1 and 3. The lower ear is provided also with an opening or slot 18 leading outwardly from the rectangular opening which receives the rectangular part of the rod. The purpose of this will appear presently. 85

The rod 13 is supported by the bracket or in the ears 12 of the bracket, and is held at a fixed position therein by a supporting and adjusting nut 19 which is screwed onto the rod 13, and rests upon the upper ear 12. 95 The rod is provided also with an upper radiator clamp 20, which is adapted to engage over the top of the radiator, as shown, this clamp being held in position by a pair of supporting and adjusting nuts 21, one arranged above and one below the clamp. 100

The hanger above described is not expensive or difficult to make or to assemble and is not easily broken, either before the hanger is put into use, or after it is mounted in 105 position, and is supporting the radiator. Additionally by simply adjusting the nut 19, the rod as a whole and the radiator is adjusted vertically, and this adjustment can be made very accurately. This accurate adjustment is of great importance to secure 110 proper drainage effects, and also to insure

that all the different hangers supporting the radiator bear equal parts of the total load supported. Additionally the upper clamp 20 can be adjusted to any height desired by an adjustment of the nuts 21, so that said clamp will assume just the desired position with respect to the lower radiator seat. This adjustment can also be made very accurately.

10 In assembling the parts, the bracket will first be secured to the wall, and then the rod is placed in position. With the special shape of the lower part of the rod and of the openings in the lower ear 12, the rod 15 can be placed in position in the ears of the bracket without the necessity of securing the bracket to the wall at a distance from the floor equal to the length of the rod, as would be the case if the openings in both ears were 20 the same, and if it were necessary to place the rod beneath the lower ear and elevate the same to cause the rod to pass through the ears. By reason of this feature, the radiator can be supported very close to the 25 floor, and in this respect my improved hanger has a great advantage over some of the hangers of which this invention is an improvement. An additional advantage of the rectangular shape of the lower part of 30 the rod is that it prevents the rod turning in the ears.

By providing a bracket having a flat body portion which is adapted to bear against the wall and having outstanding 35 ears which project horizontally from the body portion when the bracket is in position for use, the body of the bracket and the heads of the bolts which secure the bracket in place, may be entirely plastered 40 over, leaving visible only the end portions of the ears. The number of such hangers which are required to support a radiator will, of course, depend upon the length of the radiator. At least two will be used, and 45 more if necessary.

Having thus described my invention, what I claim is:

1. A hanger for a wall radiator comprising supporting means adapted to be secured 50 to the wall, a rod mounted in said support-

ing holding means, means on said rod for holding the rod at a fixed height relative to said supporting means and for adjusting the position of the rod, said rod having at its lower end a radiator seat, and an upper 55 radiator clamp supported on said rod above the holding means.

2. In a hanger for a wall radiator, a bracket adapted to be secured to the wall and having outstanding members, a rod 60 passing through said members, a nut on said rod engaging the upper member and holding said rod in position relative to the bracket, said rod having at its lower end a laterally extending portion constituting a 65 radiator seat, an upper radiator engaging device mounted on said rod above said nut, and means adjustable along said rod for holding said device any desired distance from the lower radiator seat. 70

3. In a hanger for a wall radiator, supporting means adapted to be secured to the wall and having outstanding members, a radiator supporting rod passing through said members and having upper and lower 75 radiator engaging means, the lower portion of the rod being enlarged in one direction relative to the upper portion, said lower member having a slot leading outwardly from the part of the lower member which 80 receives the enlarged part of the rod.

4. In a hanger for a wall radiator, a bracket adapted to be secured to the wall, said bracket having outstanding ears, a rod supported by said bracket and having at its 85 lower end a radiator seat, the upper part of the rod being round and the lower part rectangular in cross section, the lower ear having a rectangular opening through which the rectangular part of the rod passes, and having a slot leading outward from said opening, said slot having a width equal substantially to the diameter of the upper part 90 of the rod.

In testimony whereof, I hereunto affix my 95 signature in the presence of two witnesses.
GEORGE I. CHITTENDEN.

Witnesses:

L. I. PORTER,
A. F. Kwis.

It is hereby certified that in Letters Patent No. 1,172,582, granted February 22, 1916, upon the application of George I. Chittenden, of Cleveland, Ohio, for an improvement in "Hangers for Wall-Radiators," errors appear in the printed specification requiring correction as follows: Page 2, line 51, claim 1, strike out the word "holding"; same page, line, and claim, before the word "means", second occurrence, insert the word *holding*; and that the said Letters Patent should be read with these corrections therein that the same may conform to the record of the case in the Patent Office.

Signed and sealed this 21st day of March, A. D., 1916.

[SEAL.]

J. T. NEWTON,

Acting Commissioner of Patents.
